UNITED STATES PATENT OFFICE.

PHILIP C. CLOSE, OF AUGUSTA, GEORGIA.

COTTON-PRESS.

SPECIFICATION forming part of Letters Patent No. 319,196, dated June 2, 1885.

Application filed October 6, 1884. (No model.)

To all whom it may concern:

Be it known that I, PHILIP C. CLOSE, a citizen of the United States, residing at Augusta, in the county of Richmond and State of Georgia, have invented certain new and useful Improvements in Cotton and Hay Presses, of which the following is a specification, reference being had therein to the accompanying drawings.

10 This invention relates to cotton-compressors of that class in which steam is employed as the motive power; and the main object of the invention is to devise such mechanical connections between the steam-cylinder and the platen of the press as shall most directly convey the power and motion of the one to the other, and which at the same time shall be simple in construction.

Referring to the drawings, Figure 1 is a side elevation, Fig. 2 is an end elevation, and Fig. 3 a section, of a portion of a compressor constructed in accordance with my invention.

Like letters indicate like parts in all the figures.

25 To a suitable base, A, (or it may be formed as a part thereof,) is secured a steam-cylinder, B, having a supply-pipe, B', and an exhaust-pipe, B''. (See Fig. 3.) The piston B⁴ of the cylinder is provided with two upright double wedges, B⁵, arranged side by side, and with their working-faces B⁶ inclined in opposite directions. These upright wedges may be formed separate from and secured to or as a part of the piston B⁴. From the base there extend two uprights, C, and from one to the other of these, near their upper ends, extends a platen, D, of the compressor or press. The follower E of the press is constructed or slotted to slide on the uprights, and extends from 40 one to the other, as does the platen. Between the follower and the base, and at each end of the press, are arranged toggle-levers F F', having pivoted connections with the platen at E' and with the base at A'. A cross-head, G, is secured to the upper ends of the double wedges B⁵, and is adapted to slide upon the guides or uprights C, and from this head G ropes or chains H extend over pulleys H', and are provided with weights H², the function of 50 which is to counterbalance the weight of the piston-head and its wedges in order to facilitate smoothness of operation in the entire ap-

paratus. At the central joint, F², of the toggle-levers, and upon the pivot of that joint, are mounted friction-rollers I I', while at the 55 central joint and upon the pivot of the opposite toggle-levers are mounted friction-rollers J J'. The rollers I I' are adapted to travel upon the working-faces B⁶ of the outer wedges B⁵, while the rollers J J' are adapted to travel 60 upon the working-faces B⁶ of the inner wedges. Now, if the vertical edge of the wedge is cut away or provided with a large slot, as shown in dotted lines at B⁸, Fig. 3, the pivot F², upon which the rollers J J' are mounted, may be 65 made to pass inwardly from the uprights when said rollers ride upon the working-faces of the inner wedges. A similar slotting of the opposite wedges will permit the pivot F² to travel inwardly and the rollers I I' a sufficient 70 distance upon the working-face of the outer wedges to accomplish the object in view; but in order to strengthen the toggle-levers at the pivoted joint and to provide means for controlling and supporting the friction-rollers 75 without slotting the wedges, the yokes K K' are provided, which overhang and embrace the wedges, and are mounted upon the pivots F², the upper ends of the yokes being connected with the pivots E' by straps K², and in 80 this construction the members F of the toggle-levers, in connection with the outside rollers, I I', are arranged outside of the wedges, while the equivalent members of the opposite toggle pass between the wedges, and a single central arm (not shown, but similar to the arms K and arranged between them) projects downward from the yoke K, and all three embrace 85 the pivot F².

As a means of adjusting the relative position of the bed and platen so as to increase and decrease at will the extent of compression with a given throw of the piston B⁴, the upper ends of the guides C are screw-threaded and provided with miter-gear nuts C', with 90 which miter-gears C² mesh, said gears being mounted on the cross-shaft C³, arranged above the platen. Upon the cross-shaft is a grooved pulley, C⁴, (shown with its upper portion broken away,) over which a rope or chain may be 95 passed for the purpose of operating said shaft in either direction to raise or lower the platen with ropes or donkey-engine. Suitable braces, L, are employed to strengthen the structure 100

and maintain the parts in proper relative position. Now, it will be seen that as steam is supplied to the cylinder the piston will be forced from its bottom upwardly, and in its movement the wedges will spread the rolls I I' J J' outwardly from the center and from side to side, carrying with them the toggles, so as to force the latter into or nearly to an upright position, and they in turn force the follower upwardly toward the platen, thus compressing the bale, which is inserted between these elements. In this operation the direct longitudinal movement of the cylinder is utilized directly at the working-points of the toggle-levers, and thereby, without undue friction, great pressure is produced between the follower and platen. A return movement of the piston by its gravity is occasioned by cutting off the supply of steam through the pipe B 20 and opening the exhaust B².

I do not limit myself to the exact construction of detail herein shown and described, as the same may in many minor respects be varied in accordance with the skill of persons conversant with the construction of machinery of this class without a departure from the spirit of my invention.

Having described my invention and its operation, what I claim is—

- 30 1. In a cotton-compressor of the class described, a piston provided with oppositely-arranged wedges, in combination with toggle-levers provided with rollers constructed to operate in connection with said wedges, substantially as specified.
- 25 2. The combination of a steam-cylinder, a piston provided with wedges, toggle-levers provided with rollers, a platen, and a follower, substantially as specified.

3. The combination of a steam-cylinder having a piston provided with wedges, a follower, a cross-head secured to said wedges, and toggle-levers provided with rollers, substantially as specified. 40

4. The combination of the cylinder B, provided with the wedges B⁵, and the toggle-levers F F', provided with the rollers I I' J J', and the follower E, substantially as shown and described. 45

5. The combination of the cylinder B, the piston B⁴, having the wedges B³, the cross-head G, the toggle F F', provided with friction-rollers, the yokes K K', the straps K², and the piston E, substantially as shown and described. 50

6. The combination of the base having the guides C, platen D, nut C', gear C², and shaft C³, substantially as shown and described. 55

7. The combination of the base A, the cylinder B, having the supply-pipe B' and exhaust B², the piston B⁴, provided with oppositely-arranged double wedges B⁵, the cross-head G, toggle-levers F F', rolls I I' J J', yokes K K', straps K², follower E, and platen, substantially as shown and described. 60

8. The piston B⁴, provided with wedges B⁵, having oppositely-arranged working-faces B⁶, substantially as shown and described. 65

9. The toggle-levers F F', in combination with the yoke K and strap K², substantially as shown and described. 70

In testimony whereof I affix my signature in presence of two witnesses.

PHILIP C. CLOSE.
